FIG 3

FIG 4

FIG 5

Harry W. Smith Inventor

By F. E. Shannon

Attorney

UNITED STATES PATENT OFFICE.

HARRY W. SMITH, OF AKRON, OHIO.

GOLF PRACTICING AND EXERCISING DEVICE.

Application filed June 1, 1921. Serial No. 474,064.

To all whom it may concern:

Be it known that I, HARRY W. SMITH, a citizen of the United States, residing at Akron, in the county of Summit and State 5 of Ohio, have invented new and useful Improvements in Golf Practicing and Exercising Devices, of which the following is a specification.

This invention relates to improvements in 10 golf practicing and exercising devices and has particular relation to certain new and useful improvements in devices of the character shown in my pending application, filed December 17, 1920, Serial Number 431,448.

15 It is an object of the invention to provide a golf practicing device which may be used to advantage in acquiring proficiency in accurately striking a golf ball.

A further object is to provide a device 20 which will include a strong, durable ball, elastically connected to a suitable base so as to be capable of being driven a considerable distance from said base and which when struck with a golf club will be propelled 25 therefrom and automatically returned thereto and will indicate by its line of travel the nature of the stroke so that the accuracy or inaccuracy thereof may be easily determined.

30 Other objects are to provide a device of the character above indicated, having a ball which may be subjected to constant use for a long period of time without breaking or being otherwise rendered unfit for use and 35 to provide an elastic connecting member which will be very durable and be capable of great extensibility and be provided with new and efficient means for detachably securing the ball thereto and to provide a 40 new and improved base member to which the connecting member may be anchored and which will permit the free stretching of said connecting member.

The above and additional objects are 45 accomplished by the novel construction, combination and arrangement of parts herein- 50 after described and illustrated in the accompanying drawing, in which I have shown a preferred embodiment of the invention, it being understood that the invention is 55 capable of various adaptations and that changes and alterations may be made or substitutions resorted to which come within the scope of the claims hereunto appended.

55 In the drawings in which similar nu-

merals of reference have been employed to indicate the same or like parts as they may occur in the several views:—

Figure 1 is a perspective view showing 60 my improved device.

Figure 2 is a central, vertical sectional view of an improved form of ball used in carrying out the invention and also showing in side elevation my improved elastic connecting member and illustrating in central 65 vertical section the means employed to secure the connecting member to the ball.

Figure 3 is a perspective view of the disk 70 employed in securing the connecting member to the ball and also illustrating a portion of the connecting member attached thereto.

Figure 4 is a central, longitudinal sectional view of my improved device taken as indicated by the lines 4—4 of Figure 5.

Figure 5 is a bottom view of my improved 75 device and also showing by dotted lines the manner in which the ball may be propelled therefrom.

Referring now to a detailed description of the invention, the numeral 1 indicates a base 80 member which in the particular embodiment of the invention shown is in the form of a rectangular mat. A centrally positioned substantially V-shaped notch 2 is formed in one of the short sides of said base member and a 85 centrally positioned longitudinally directed slot 3 is formed in the bottom thereof so as to communicate with said notch and extend rearwardly therefrom and terminate in an annular groove 4 which is preferably 90 positioned at a point adjacent the rear end of the mat 1. The annular groove 4 is undercut at its inner circumferential edge, thus providing a button 5, the purpose of which 95 will be hereinafter described.

The numeral 6 indicates an elastic connecting member which may be constructed of any suitable material, but which I prefer to construct of hollow rubber tubing, one end of the tube is turned back upon itself 100 and secured by being wrapped with rubber thread 7 so as to form the loops 8 and 9, either of which may be positioned over the button 5 to secure the elastic member 6 to the base 1. By closing the tube 105 6 at, one end by wrapping rubber thread therearound as at 14 and by closing the same at the other end by the wrapping 7, I have provided a hollow rubber connecting member which is filled with air and 110

will therefore withstand being struck with a relatively sharp club without being cut or broken.

The numeral 10 denotes a disk which is preferably formed of felt or other relatively soft material, and the numerals 11 and 12 indicate holes which extend through the said disk 10. The end 13 of the tube 6 is threaded upwardly through the hole 12 and downwardly through the hole 11 and is secured to itself as at 14 by a wrapping of rubber thread or other suitable material. The ball 15 is hollow and is composed of elastic material preferably of soft rubber composition which will possess sufficient stiffness to form an easily collapsible ball that will almost instantly return to its normal shape after being collapsed. The ball 15 is provided with a hole 16 which is formed in the bottom thereof to receive the connecting member 6. The numeral 17 indicates a downwardly projecting annular flange which is integral with the body of the ball 15 and surrounds the hole 14 so as to form a base or tee which is substantially cylindrical in form and projects radially from said ball.

In securing the member 6 to the ball 15, the bottom of the ball is stretched and the hole 16 is thus enlarged sufficiently to permit the disk 10 to be inserted therein, whereupon the ball is permitted to resume its normal shape and the disk is securely retained therein as shown in Figure 2. This method of securing the cord to the ball is particularly efficient inasmuch as the disk 10 is freely rotatable in the ball, thus preventing a twisting of the cord when the ball is struck with the golf club. The numeral 18 denotes a hole which is formed in the body of the ball to permit the free passage of air therethrough.

In use, the connecting member 6 is secured to the ball 15 as hereinbefore set forth and one of the loops 8 and 9 is secured on the button 5. The member 6 is carried forward in the groove 3 so that the ball 15 is positioned on the upper face of the mat 1 and is retained thereon at a point just above the apex of the notch 2. The base member 1 is then placed flat on the floor or other surface and the ball is struck with a golf club in exactly the same manner as a golf ball is hit in regular play. If a straight ball is desired and the ball is struck accurately, it will be propelled forwardly as shown by the dotted line 20. If, however, the ball is sliced, intentionally or unintentionally, it will be driven forward substantially as indicated by the dotted line 21, and likewise if the ball is pulled, it will travel as indicated by the dotted line 19. If the ball is topped or hit too high or too low the play may be observed and accurately judged by

the distance the ball travels from the mat. The ball 15 when hit will partly collapse and the air in the ball escapes through the holes 16 and 18. As soon as the ball is out of contact with the club it assumes its normal shape and after being propelled forwardly is instantly returned to the base 1, the shape of the notch 2 being such that the ball is automatically teed.

It will thus be seen that I have provided a simple, durable, inexpensive device which, while embodying the broad features of my former invention, which is fully described in my pending application to which reference is hereinbefore made presents several decided improvements over the structure illustrated and described.

Having thus illustrated my invention and described the same in detail, what I claim as new and desire to secure by Letters Patent is:—

1. In a device of the class described, a base member, an object member and an elastic connecting member therebetween, said object member being a hollow ball of relatively stiff elastic material and having an opening in the bottom thereof one end of said connecting member extending into said opening and means associated with said end to loosely secure the same within said object member, said object member being mounted on the upper face of said base member and normally held in position thereon by said connecting member.

2. In a device of the class described, a base member, an object member and an elastic connecting member therebetween, said object member being a hollow rubber ball having a tee formed integral therewith and an opening extending through said tee, means to rotatably secure one end of said connecting member in said opening and means to detachably secure the other end thereof to the underside of said base member.

3. In a device of the class described, a mat having a notch in one end thereof, a ball adapted to be positioned on the upper face of said mat at a point above the apex of said notch, a groove in the under face of said mat, said groove leading from the apex of said notch to a point adjacent the opposite end of said mat, an elastic member, means to secure one end thereof in said groove, the other end thereof being secured to said ball.

4. In a device of the class described, a mat having a notch in one end thereof, a groove in the under face of said mat, said groove leading from the apex of said notch to a point adjacent the other end of said mat, a button in said groove, an elastic member having one end thereof detachably secured to said button and extending longitudinally through said groove to the apex

of said notch and a ball detachably secured to the other end of said member, substantially as and for the purposes set forth.

5. In a device of the class described, a base member, an object member and a hollow rubber tube connecting said members.

6. In a device of the class described, a base member, an object member and an elastic connecting member, said elastic connecting member comprising a rubber tube, means to detachably secure one end of said tube to said base member and means to detachably secure the other end thereof to said object member.

15 7. In a device of the class described, a base member, an object member and an elastic connecting member, said object member comprising a hollow ball composed of relatively stiff elastic material, an opening in the bottom of said ball, a retaining member on one end of said connecting member, said retaining member adapted to be inserted into the ball through said opening to retain the same on said connecting member.

25 8. In a device of the class described, a base member and an object member positioned thereon at a point adjacent the forward edge thereof, a hollow elastic connecting member arranged to normally retain the object member at said point and adapted to return the same thereto when moved therefrom, said object member comprising a hollow ball of relatively stiff material, an opening in the bottom of said ball and a down-

wardly projecting cylindrical tee concentrically arranged around said opening.

9. In a device of the class described, a base member, an object member and a hollow rubber tube connecting said members, 40 said tube being filled with air and closed at each end.

10. In means for connecting a ball to an anchoring member, a hollow tube of elastic rubber containing air and closed at both 45 ends.

11. In means for connecting a ball to an anchoring member, a hollow tube of elastic rubber containing air and having each end thereof turned back upon itself and secured 50 in a loop by rubber thread wound there-around.

12. In a device of the class described, a mat, a notch at the forward end thereof, a ball positioned on the upper face of said 55 mat above the apex of said notch, an elastic connecting member having one end secured to said ball and extending under said mat with the other end thereof secured at a point adjacent the rear end thereof. 60

13. In a device of the class described, a hollow rubber ball, an opening in the bottom thereof, a tee around said opening, a hollow elastic cord, a felt button secured to one end of said cord and inserted in said 65 opening to retain the ball on said cord.

In testimony whereof I have hereunto set my hand.

HARRY W. SMITH.
